UNITED STATES PATENT OFFICE.

HALLACK C. BALL AND JOSEPH Z. WINDER, OF RICHMOND, INDIANA, ASSIGNEES TO RICHMOND FIREPROOF DOOR COMPANY, OF RICHMOND, INDIANA, A CORPORATION OF INDIANA.

ELECTRIC INTERLOCK FOR ELEVATOR DOORS.

Application filed April 30, 1925. Serial No. 26,951.

Our invention relates to an electric interlock for elevator doors, and more particularly to a construction by which a switch mechanism for controlling the circuit to the 5 motor for operating the elevator car, will be automatically opened or closed simultaneously with the release or setting of the lock mechanism for permitting, or preventing, the opening of elevator doors, when said 10 doors are closed, and preventing the application of power to the elevator operating motor; except when all doors in a shaft are closed and locked.

The invention is particularly applicable 15 for use with elevator doors of the counterbalanced, or related, types which doors consist of two sections having flexible connections by which said sections are caused to have simultaneous movement in a substantially vertical plane; but in opposite directions when opening or closing the door. These two sections, when the door is in the 20 closed position, have their adjacent or abutting edges meet at approximately midway of 25 the height of the door opening.

Such doors are extensively used in warehouses, and the different openings in an elevator shaft or well are closed by similar doors, each door being equipped with an 30 electric interlock, so that movement of the car is prevented unless all doors in the shaft are completely closed and locked.

This general arrangement is old and well known in the art, our invention relating 35 more particularly to a combined mechanical lock and electric interlock mechanism so constructed as to ensure accuracy in the timing of the operation of these two mechanisms, so that while the mechanical locking of the 40 door is entirely independent of the actuation of the electric interlock, such parts will both be controlled through one and the same mechanism, and the actuation of one will be co-ordinated with the actuation of the other.

45 By an arrangement such as is above described, the electric interlock mechanism is relieved from all of the strains and stresses incidental to the holding of the doors in the closed position, and likelihood of breakage 50 of the interlock through overrunning of the door section carrying one of the parts of the locking mechanism is avoided.

In the installation of elevator door equipment particularly in case of the construction of new buildings, the parts are manufactured to accord with the building plans, but in erection work, it is frequently found that the dimensions in the plan are not strictly adhered to, so that it is required to adapt the elevator door installation to conditions 55 found in a shaft which are changed from those for which the elevator door equipment was constructed to meet.

To facilitate the installation of the equipment, we so construct the interlock portion 60 of the locking mechanism that it may be readily mounted upon the wall angle carrying the guide rails for the doors, and may be adjusted after installation either to compensate for variation from the building 65 plans, or for wear after long use of the doors, in order to ensure positive actuation of the electric interlock by the door locking mechanism whether this be for the purpose 70 of opening or closing the circuit to the elevator actuating motor.

The invention consists primarily in an 75 electric interlock for elevator doors embodying therein the combination with a door, composed of oppositely and vertically movable sections, flexible connections between 80 said sections, and a guide structure for said sections upon opposite sides of a door opening, of a stop carried by said guide structure, a laterally slidable bolt upon one of 85 said door sections, co-operating with said stop to lock the door in the closed position, a casing carried by said guide structure, fixed contacts therein in circuit with the elevator car actuating motor, a movable contact 90 co-operating with said fixed contacts, a member carried by said movable contact, and projecting beyond said casing and into engageable relation with said bolt, and means operative upon said movable contact, whereby 95 it has a normal tendency to open the circuit to the motor as said bolt is disengaged therefrom; and in such other novel features of construction and combination of parts as are hereinafter set forth and described and more 100 particularly pointed out in the claims hereto appended.

Referring to the drawings,

Fig. 1 is a fragmentary portion of an ele-

vator door adjacent the meeting point of the two sections of the door, showing a combined locking mechanism and electric interlock embodying our invention;

5 Fig. 2 is a view upon a larger scale showing the details of the electric interlock mechanism; and

Fig. 3 is an elevation from the right of Fig. 2.

10 Like letters refer to like parts throughout the several views.

In the embodiment of the invention shown in the drawings, a portion of the upper section of a door is shown at *a* and a portion 15 of the lower section at *b*. The guide structure of these sections comprises a wall angle *c* having a guide rail *d* attached thereto with which shoes *d'* upon the door sections *a* and *b* respectively co-operate in controlling the 20 opening and closing movement of the door sections. This guide structure may be of any desired construction, one well known type being shown and described.

Carried by the wall angle *c* is a stop 25 member *e*, a co-operating member *e'* being secured to the side bar of the upper door section *a*, the members *e—e'* being for the purpose of preventing the upper door section from falling downwardly of the shaft 30 in the event of breakage of the usual connections between the section *a* and *b*, a portion of which is shown at *f*. The connections *f* are united with the hanger bar *f'* of the lower door section.

35 Each section *a* and *b* is provided with the usual collapsible guides *g* engaging the edge of the guide rail *d* in a manner to secure the desired sliding fit of the door with said guide members under normal conditions, while permitting expansion of the 40 door in the event of fire.

The mechanisms heretofore described are duplicated upon opposite sides of the door.

When opening a door, the section *a* moves 45 upwardly and the section *b* downwardly, the movement of these parts being reversed in closing the door, the edges of the two sections adjacent the hanger bar substantially meeting at approximately midway 50 of the height of the door opening. Such doors ordinarily lap the door opening at the top, bottom and both sides when the door is in the closed position.

In elevator doors of the type heretofore 55 described, it is customary to provide a positive mechanical locking mechanism operable from the inside of the shaft only, for keeping the doors in the closed position, and permit their being opened only when an elevator is at the floor closed by a door. The 60 electric interlock used with such mechanical locks is for the purpose of preventing a car from leaving a floor at which the door is open until the door has been fully 65 closed and locked. The electric interlock

structure usually serves as a keeper to receive the locking bolt so as to ensure the proper co-ordination of the mechanical lock and the electric interlock.

In the embodiment of the invention shown 70 in the drawings, the mechanical lock is shown as consisting of a bevelled stop member *h* secured to the wall angle *c*, and a 75 slideable bolt *i* mounted in a suitable housing *i'* upon the lower door section *b*. While in the drawings this mechanism is shown as being applied to the lower door section, it is apparent that it may, if desired, be applied to the upper door section by merely 80 reversing the position of the stop *h*, since the locking of either section, by reason of the connections between the two sections, will result in the locking of both sections. The bolt *i* is actuated by a link *i''* and the 85 usual hand operated mechanism not shown, this link being connected to a pivot *i'''* carried by the bolt *i* and moving in a slot *i''* in the housing *i'*.

Mounted upon the wall angle *c* is an 90 electric interlock mechanism which includes a casing *j* secured to said wall angle in any desired manner, having therein a switch 95 mechanism by which the circuit to the car actuating motor is controlled, the construction being such that the circuit is closed only when all doors in a shaft are closed, and is opened when any door in a shaft is open.

The general construction and electrical 100 arrangement of this interlock mechanism is old and well known in the art, and includes two fixed contacts *k—k'* carried by and insulated from the casing *j*, and a movable bridge contact *k''* carried by a stem *k'''* and 105 acted upon by a spring *k'''*. The stem *k'''* is carried by and insulated from a pivotal or rocking support *m* provided with either or both an overbalancing weight *m'* and a spring *m''* so as to cause said support to have a normal tendency to move the contact *k''* out of engagement with the fixed contacts *k—k'*. At *k''* I have shown a conduit 110 containing wires leading to the contacts *k—k'*.

The casing *j* is secured to the flange of 115 the wall angle *c* extending inwardly of the shaft upon the side thereof opposite to that from which the guide rail *d* projects, the flange of said wall angle to which the casing is secured and the flange of said guide rail, being recessed or drilled to permit the free 120 passage of a boss *n* upon the support *m* through the guide rail structure for the purpose of permitting the actuation of said pivotal support by the bolt *i* when said bolt is moving to engaging relation with the stop *h*. The boss *n* is provided with a screw-threaded socket, and adjustably mounted 125 therein is a contact member consisting of a headed screw bolt *o* extending from said boss into a position where it is engageable 130

by said bolt i . By this construction the member or bolt o may be so adjusted with relation to the support m and the locking bolt i as to ensure an accurate timing of the actuation of the support m and of the bolt i so as to preclude any possibility of the engagement of the bolt i with the stop h without such an actuation of the contact k^2 as will ensure the closing of the circuit 10 across the contacts $k-k'$, and the maintenance of a closed circuit while the door is locked. The member o is provided with a lock nut o' so that when it is once properly adjusted, the adjustment will not be interfered with by vibration in and about the elevated door equipment.

The provision of the member of bolt o and the manner of mounting the casing j upon the wall angle permits a considerable range 20 of adjustment of the casing j and the stop h to meet conditions arising from variance in dimensions between the actual structure of an elevator shaft and the plans for the building, it being possible to drill all necessary holes for the installation of this part and the cutting of the rails for the passage 25 of the boss n by the erectors on the job to secure the proper location of said stop and of the interlock vertically of the door opening. The adjustability of the member or bolt o permits adjustment of the interlock independently of the rail structure to compensate for variance in the lateral dimensions which may result by changes in dimensions of any door in a shaft.

A construction permitting adjustment of said member o , which will rarely be great, is highly desirable, since elevator door structures in their entirety are ordinarily made to special dimensions ready for assembly and installation, in a factory which may be hundreds of miles from the point of installation which is done by a traveling crew of erectors under conditions where the facilities for mechanical work are entirely lacking.

The mechanism including the bolt i , stop h and link i^2 is ordinarily duplicated at both sides of the door opening, the interlock mechanism, however, being used only at one side of this opening.

It is also the practice to provide each door in a shaft with the same mechanical lock and interlock mechanism, the electrical portions of the various interlocks being connected in series so that all doors in a shaft must be fully closed and locked to permit the operation of the car.

The use of both an overbalancing weight m' and a spring m^2 is not essential, although it is not at all uncommon for building codes to require that the switch mechanism of the interlock be so constructed as to interrupt the circuit by means other than springs.

When the spring is used, however, it is mere-

ly to cause a sharp break of the movable contact and the fixed contacts.

By the construction herein described the electric interlock mechanism is relieved from all breaking stresses either from the load 70 of the door, through the bolt i , or from a possible overturning of the door sections as a result of a violent actuation of a door.

The member o is readily accessible for purposes of adjustment, and yet its adjustment cannot in any way contribute toward the closing of the circuit to permit the operation of the elevator car, except through the medium of the bolt i .

By securing the casing j upon the side of the inwardly directed flange of the wall angle e opposite to that carrying the guide rail d and by so constructing the pivotal or rocking member m , that merely a small opening in the flange supporting the casing 85 j is required, the cutting out of portions of the wall angle adjacent the point of connection of the casing j therewith is avoided so that adjustment of said casing along said wall angle to any desired extent may be 90 made.

It is not our intention to limit the invention to the precise details of construction shown in the accompanying drawings, it being apparent that such may be varied 95 without departing from the spirit and scope of the invention.

Having described the invention, what we claim as new and desire to have protected by Letters Patent, is:

1. An electric interlock for elevator doors embodying therein the combination with a door, composed of oppositely and vertically movable sections, flexible connections between said sections, and a guide structure for said sections upon opposite sides of a door opening, of a stop carried by said guide structure, a laterally slideable bolt upon one of said door sections, co-operating with said stop to lock the door 105 in the closed position, a casing carried by said guide structure, fixed contacts therein in circuit with the elevator car actuating motor, a movable contact co-operating with said fixed contacts, a member carried by said 110 movable contact, and projecting beyond said casing and into engageable relation with said bolt, and means operative upon said movable contact, whereby it has a normal tendency 115 to open the circuit to the motor as said bolt is disengaged therefrom.

2. An electric interlock for elevator doors embodying therein the combination with a door, composed of oppositely and vertically movable sections, flexible connections between said sections, and a guide structure for said sections upon opposite sides of a door opening, of a stop carried by said guide structure, a laterally slideable bolt upon one of said door sections, co-operating with said 125

stop to lock the door in the closed position, a casing carried by said guide structure, fixed contacts therein in circuit with the elevator car actuating motor, a movable contact co-operating with said fixed contacts, a member adjustably mounted upon said movable contact, and projecting into engageable relation with said bolt, whereby said member may be adjusted in relation to said 10 slideable bolt to compensate for variances in the widths of different door openings, and means operative upon said movable contact, whereby it has a normal tendency to open the circuit to the motor as said bolt is disengaged therefrom.

3. An electric interlock for elevator doors embodying therein the combination with a door, composed of oppositely and vertically movable sections, flexible connections between said sections, and a guide structure for said sections upon opposite sides of a door opening, of a stop carried by said guide structure, a laterally slideable bolt upon one of said door sections, co-operating 20 with said stop to lock the door in the closed position, a casing carried by said guide structure, fixed contacts therein in circuit with the elevator car actuating motor, a movable contact co-operating with said fixed contacts, said guide structure having an opening therethrough, a member carried by said movable contact, and projecting through said opening in said guide structure and into engageable relation with said 30 bolt, and means operative upon said movable contact, whereby it has a normal tendency to open the circuit to the motor as said bolt is disengaged therefrom.

4. An electric interlock for elevator doors embodying therein the combination with a door, composed of oppositely and vertically movable sections, flexible connections between said sections, and a guide structure for said sections upon opposite sides of a door opening, of a stop carried by said guide structure, a laterally slideable bolt upon one of said door sections, co-operating with said stop to lock the door in the closed position, a casing carried by said guide structure, fixed contacts therein in circuit with the elevator car actuating motor, a movable contact co-operating with said fixed contacts, said guide structure having an opening therethrough, a member adjustably mounted upon said movable contact, and projecting through said opening into engageable relation with said bolt, whereby said member may be adjusted in relation to said slideable bolt to compensate for variances in the 50 widths of different door openings, and means operative upon said movable contact, whereby it has a normal tendency to open the circuit to the motor as said bolt is disengaged therefrom.

5. An electric interlock for elevator

doors embodying therein the combination with a door, composed of oppositely and vertically movable sections, flexible connections between said sections, and a guide structure for said sections upon opposite sides of a door opening, comprising a wall angle having an inwardly directed flange and an angular guide rail secured to said inwardly directed flange of said wall angle, of a stop carried by said guide structure, a laterally slideable bolt upon one of said door sections, co-operating with said stop to lock the door in the closed position, a casing carried by said inwardly directed flange of said wall angle upon the side thereof opposite to that to which said guide rail is connected, fixed contacts therein in circuit with the elevator car actuating motor, a movable contact co-operating with said fixed contacts, said inwardly directed wall angle flange having an opening therethrough, a member carried by said movable contact, and projecting through said opening in said guide structure and into engageable relation with said bolt, and means operative upon said movable contact, whereby it has a normal tendency to open the circuit to the motor as said bolt is disengaged therefrom.

6. An electric interlock for elevator doors embodying therein the combination with a door, composed of oppositely and vertically movable sections, flexible connections between said sections, and a guide structure for said sections upon opposite sides of a door opening, of a stop carried by said guide structure, a laterally slideable bolt upon one of said door sections, co-operating with said stop to lock the door in the closed position, a casing carried by said guide structure, fixed contacts therein in circuit with the elevator car actuating motor, a movable contact co-operating with said fixed contacts, a member carried by said movable contacts, and projecting beyond 100 said casing and into engageable relation with said bolt, an overbalancing weight operative upon said movable contact, whereby it has a normal tendency to open the circuit to the motor as said bolt is disengaged therefrom, and a spring supplementing the action of 110 said overbalancing weight.

7. An electric interlock for elevator doors embodying therein the combination with a door, composed of oppositely and vertically movable sections, flexible connections between said sections, and a guide structure for said sections upon opposite sides of a door opening, comprising a wall angle having an inwardly directed flange and an angular guide rail secured to said inwardly directed flange of said wall angle, of a stop carried by said guide structure, a laterally slideable bolt upon one of said door sections, co-operating with said stop to lock the door 120 in the closed position, a casing carried by 125

- said inwardly directed flange of said wall angle upon the side thereof opposite to that to which said guide rail is connected, fixed contacts therein in circuit with the elevator car actuating motor, a movable contact cooperating with said fixed contacts, said inwardly directed wall angle flange having an opening therethrough, a member carried by said movable contact, and projecting through said opening in said wall angle flange and into engageable relation with said bolt, an overbalancing weight operative upon said movable contact, whereby it has a normal tendency to open the circuit to the motor as said bolt is disengaged therefrom, and a ¹⁵ spring supplementing the action of said overbalancing weight.

In witness whereof we have hereunto affixed our signatures this 27th day of April, 1925.

HALLACK C. BALL.
JOSEPH Z. WINDER.
